United States Patent Office.

GEORGE M. MORRIS, OF COHOES, NEW YORK.

Letters Patent No. 64,130, dated April 23, 1867.

IMPROVEMENT IN OILING DEVICE FOR JOURNAL-BOXES.

The Schedule referred to in these Letters Patent and making part of the same.

TO ALL WHOM IT MAY CONCERN:

Be it known that I, G. M. MORRIS, of Cohoes, Albany county, New York, have invented a new and improved Oiling Device for Journal-Boxes; and I do hereby declare that the following is a full, clear, and exact description thereof, which will enable others skilled in the art to make and use the same, reference being had to the accompanying drawings, forming part of this specification.

Figure 1 is a cross-section of a journal-box, to which my improved oiling device has been attached, taken through the line *x x*, fig. 2.

Figure 2 is a longitudinal section of the same, taken through the line *y y*, fig. 1.

Figure 3 is a detail view of the inclined plate.

Similar letters of reference indicate corresponding parts.

My invention has for its object to furnish an improved device for oiling journals, which shall be simple in construction, effective in operation, and easily removed and replaced when worn; and it consists in forming inclined shoulders in the oil reservoir formed in the journal-box, and in the inclined removable slotted plate, in combination with the inclined shoulders of the journal-box and with the oiling disk; the whole being constructed and arranged as hereinafter more fully described.

A is the lower, and B the upper part or cap of the journal-box. The middle part of the lower part A is cut away, or chambered, so as to form an oil reservoir, C, as shown in figs. 1 and 2, leaving a rib, *a'*, so that the side of the journal may be in contact with a bearing surface throughout the entire length of the journal-box. Upon the sides of the reservoir or chamber C are formed inclined shoulders D, as shown in fig. 1. These shoulders D may be cast solid with the journal-box, or they may be formed separately and placed within the chamber C, as may be desired or convenient. E is a metal plate of such a length as to extend from the bottom of the chamber C to its upper edge, resting upon the inclined shoulders D, and equal in breadth to the breadth of the said chamber C, so that it may fit accurately into its seat. The steadiness of the plate may be increased by making the sides of the chamber C and the edges of the plate E slightly tapering, or wedge-shaped, as shown in figs. 2 and 3. The plate E is slotted longitudinally, as shown in figs. 1, 2, and 3, for the reception of the oiling disk F, the journals G of which revolve upon the face of the said plate E, as shown in figs. 1 and 2. The lower edge of the plate E is notched, and the lower end of the slot through said plate is enlarged, as shown in figs. 2 and 3, to allow the oil to have a free passage. By this construction the plate E prevents the shoulders D from becoming worn by the journals G; and should the plate D become worn it may be turned over or removed and replaced with a new one, without interfering with the operation of the journal, and while the said journal is in motion. It also enables a large or small oiling disk, F, to be used, as may be desired or convenient.

I claim as new, and desire to secure by Letters Patent—

1. Forming inclined shoulders D in the oil chamber or reservoir C of the journal-box, substantially as herein shown and described and for the purpose set forth.
2. The inclined removable slotted plate E, in combination with the inclined shoulders D of the journal-box and with the oiling disk F, substantially as herein shown and described and for the purpose set forth.

The above specification of my invention signed by me this 28th day of January, 1867.

G. M. MORRIS.
